[57] **CLAIM**

The ornamental design for table lamp, as shown and described.

DESCRIPTION

FIG. 1 is a front view of the table lamp of my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

The cross-hatching is fragmentarily shown on the shade for convenience of illustration, it being understood that the cross-hatching is uniformly continuous over the surface on which it appears.

FIG. 1

FIG. 2

FIG. 3

FIG. 4

FIG. 5

FIG. 6

FIG. 7
